C. W. GOULD.
AUTOMATIC CONTROL FOR BURNER VALVES.
APPLICATION FILED JAN. 14, 1914.

1,135,891.

Patented Apr. 13, 1915.

UNITED STATES PATENT OFFICE.

CHARLES W. GOULD, OF LOS ANGELES, CALIFORNIA.

AUTOMATIC CONTROL FOR BURNER-VALVES.

1,135,891.

Specification of Letters Patent. Patented Apr. 13, 1915.

Application filed January 14, 1914. Serial No. 812,004.

To all whom it may concern:

Be it known that I, CHARLES W. GOULD, a citizen of the United States, residing at Los Angeles, in the county of Los Angeles, State 5 of California, have invented new and useful Improvements in Automatic Control for Burner-Valves, of which the following is a specification.

This invention relates to an automatic control for burner valves.

It is the object of this invention to provide an automatic control for the needle valve of burners by which the discharge of fluid fuel from the burner will be regulated 15 to maintain an approximately uniform temperature in the combustion chamber of furnace.

Another object is to provide an adjustment whereby the automatic valve controlling means can be set to operate the valve so that the latter will feed a predetermined quantity of oil through the burner, and by 20 which complete closing of the valve by the automatic valve control can be prevented.

Another object is to provide means whereby the needle valve can be manually closed and opened independent of the automatic control means.

The invention primarily resides in a needle valve stem having a pinion loosely mounted thereon, a pivoted toothed segment meshing with said pinion, thermostatic controlled means for rocking the segment to rotate the pinion, and means for detachably 30 connecting the pinion to the valve stem, whereby the valve stem can be rotated by means of the pinion or rotated manually independent of the pinion.

The invention is illustrated in the accompanying drawings, in which:

Figure 1 is a front elevation of a furnace showing the invention as applied.

Fig. 2 is a detail in front elevation of the valve stem connections with portions broken away. Fig. 3 is a vertical section on the line 3—3 of Fig. 2, illustrating the connections of the valve stem as positioned for automatic rotation of the valve stem. Fig. 4 is a detail in elevation on the line 4—4 of Fig. 50 2, with portions broken away showing the connections of the valve stem as positioned for manual operation of the latter.

More specifically, 5 indicates the threaded stem of a needle valve 6 of the usual type, adapted to regulate the flow of fluid fuel 55 from a supply pipe 7 to a discharge pipe 8 connecting with a suitable burner through a

tapered port 9 in the valve casing 10. The outer portion of the valve stem 5 is formed with a cylindrical hub 11 in axial alignment 60 with the valve stem on which a spur pinion is revolvably mounted and held against longitudinal movement in one direction on the valve stem by means of a shoulder 14 on the latter against which the rear side of the 65 pinion 12 slidably abuts.

The outer face of the pinion 12 is formed with radially extending V-shaped teeth 15 which are adapted to be engaged by corresponding teeth 16 on the rear face of a 70 hand-wheel 17 slidably mounted on a rectangular extension 18 on the valve stem, which extension forms a continuation of the hub portion 11. The teeth 15 and 16 are designed to be normally held in engagement 75 with each other by means of a wing-nut 19 screwed on a threaded stud 20 projecting from the end of the squared portion 18 of the valve stem; the inner face of the wing-nut 19 bearing against the outer face of the 80 hub portion of the hand-wheel 17 when disposed in its innermost position on the threaded stem 20.

Arranged in constant mesh with the pinion 12 is a toothed segment 21 which is pivoted concentric with its arcual face on a pivot pin 22 carried by a standard 23 carried on any suitable support. The segment 21 is designed to be rocked by means of a thermostatic controlled device of any suitable description, but which is here shown as consisting of a rocker arm 24 pivoted at 25 to a suitable support directly above the toothed segment 21 and a thermostat 26 having a member 27 adapted to engage the underside of the rocker arm 24 to one side of the pivot 25. The rocker arm 24 is connected at its outer ends to the ends of the toothed segment 21 by means of chains 28 or other suitable connections. 95

Adjustably mounted on the rocker arm 24 on opposite sides of its pivotal support 25 are counter-weighting members 29 and 30 which are adapted to be adjusted on the rocker arm 24 to establish a balance of the 100 latter on its pivot so that the thermostat 26 can readily effect the operation of the rocker arm 24 and the segment 21. The thermostat 26 may be of any desired type and affixed to any suitable point on the furnace structure 110 wherein it will be operated by the heat generated therein. In this case the thermostat 26 is shown as comprising an expandible and contractible bellows-like structure to which

the rocker-arm engaging member 27 is attached. The expandible structure contains a fluid adapted to cause expansion and contraction of the thermostat by variations in temperature, as is common in such devices. The thermostat is here shown as attached to a steam-pipe 31 leading from a furnace 32.

In the operation of the invention, the valve 6 is first manually adjusted in relation 10 to the port 9 to permit the discharge of the fluid fuel to the burner according to the intensity of the flame desired; this manual adjustment of the valve being accomplished by first partially unscrewing the wing-nut 19 from the threaded stem 20 as illustrated in Fig. 4, and then withdrawing the teeth 16 on the hand wheel 17 out of engagement with the teeth 15 on the pinion 12; the latter operation being effected by sliding the hand 20 wheel 17 outwardly on the squared portion 18 of the valve stem, as shown in Fig. 4. The valve stem 5 can then be rotated in either direction through the medium of the hand wheel 17 independent of the pinion 12. 25 When the desired adjustment of the valve has been obtained the hand wheel 17 is moved into engagement with the pinion 12 and locked in such engagement by means of the wing nut 19; the parts being then positioned 30 as shown in Fig. 3.

The thermostat 26 is then set or adjusted as is common in these devices to operate when the temperature in the furnace increases above a predetermined degree to rock 35 the arm 24 so as to transmit a rocking movement to the segment 21 and thereby rotate the valve stem 5 through the medium of the pinion 12 and hand wheel 17 in such direction as to advance the valve 6 into the port 9 40 and restrict the flow of fluid fuel therethrough thereby reducing the intensity of the flame and consequently diminishing the heat produced by the combustion of the fuel at the burner; the thermostat 26 being operated 45 when the temperature in the furnace falls below a predetermined degree to relieve the rocker arm 24 in such manner that the counter-weight 29 or 30 will restore the rocker arm to a point below its normal position so 50 as to rock the segment 21 and rotate the valve stem 5 in the opposite direction to open the valve wider and permit the increased flow of fluid fuel to the burner. The device will thus automatically operate to maintain 55 an approximately uniform feed of the fluid fuel to the burner and will vary the feed according to variations of temperature in the furnace or a portion thereof to which the thermostat 26 is attached.

60 By providing a detachable connection between the pinion 12 and the valve stem 5 the latter can be manually adjusted at any time either to increase the flow of fluid fuel to the

burner or to close the valve; this manual operation of the valve being accomplished as 65 before described by loosening the wing-nut 19 and moving the hand wheel 17 out of engagement with the pinion 12. The pinion 12 will be held against longitudinal movement on the shaft 5 by means of the wing- 70 nut 19 bearing against the hand wheel 17 which in turn bears against the pinion 12 and crowds it against the shoulder 14 on the valve stem 5. The provision of a spur pinion and a toothed segment permits of the 75 longitudinal movement of the valve stem 5 as the latter is advanced or retracted in its casing; the teeth on the pinion 12 sliding longitudinally of the teeth on the segment 21 in constant engagement therewith during 80 such movement of the valve stem.

What I claim is:

1. In an automatic control for burner valves, the combination with a needle valve stem of a hand-wheel on said stem a pinion revolvably mounted on the stem, means for detachably connecting the pinion to the hand-wheel on the stem, a toothed segment meshing with said pinion, and thermostatic controlled means operating on said segment for 85 automatically rotating the valve stem.

2. In a device for automatically operating needle valves, the combination with a needle valve stem of a pinion revolvably mounted on said valve stem, a hand wheel on said valve stem turnable therewith, and slidably longitudinally thereon, means for detachably connecting the hand wheel to the pinion, a toothed segment meshing with said pinion, and thermostatic controlled means for 95 rock-100 ing the segment to revolve the valve stem through the hand wheel.

3. In a thermostatic control for needle valves, a pivoted toothed segment, a pinion engaged by said segment, a valve stem on which said pinion is revolvably mounted, a hand wheel slidably mounted on the valve stem and revoluble therewith, means for connecting the pinion to the hand wheel whereby rotation of the pinion will rotate 110 the valve stem, said means adapted to be disengaged to permit manual operation of the valve stem independent of the pinion, means for locking the hand wheel and pinion in engagement with each other, and thermostatic controlled means for rocking the segment to rotate the valve stem through the hand wheel and pinion.

In witness that I claim the foregoing I have hereunto subscribed my name this 30th 115 day of December, 1913.

CHARLES W. GOULD.
